(57) **CLAIM**

The ornamental design for a golf club head side, as shown and described.

DESCRIPTION

This application is related to the following commonly-owned co-pending design patent applications: "Golf Club Head," Ser. No. 29/134,594, and "Golf Club Head Bottom," Ser. No. 29/134,595.

FIG. 1 is a top front perspective view of a golf club head showing the golf club head side of my new design, that portion of the golf club head shown in phantom is not part of the design sought to be patented and is provided for environmental purposes only;

FIG. 2 is a toe end elevational view thereof;

FIG. 3 is a heel end elevational view thereof;

FIG. 4 is a rear elevational view thereof; and,

FIG. 5 is a rear bottom perspective view thereof.
